UNITED STATES PATENT OFFICE.

DAVID MOSMAN, OF WEST MERIDEN, CONNECTICUT, ASSIGNOR TO BRADLEY & HUBBARD, OF SAME PLACE.

DESIGN FOR FIGURE FOR LAMP-BASE.

Specification forming part of Design No. 5,476, dated January 16, 1872.

To all whom it may concern:

Be it known that I, DAVID MOSMAN, of West Meriden, in the county of New Haven and State of Connecticut, have invented a new Design for Figure for Lamp-Base; and I do hereby declare the following, when taken in connection with the accompanying illustration, to be a full, clear, and exact description of the same, and which said drawing constitutes part of this specification, and represents a front view.

This invention relates to a design for the lower portion of a standard for lamps; and it consists in the figure hereinafter described and fully shown in the accompanying illustration.

On a base is represented a boy sitting, with a dog standing resting his fore-paws and head

upon the boy's leg, as shown in the accompanying illustration. This figure, when used in connection with a lamp-standard, has a post or stump at the rear of the boy, and this stump is used in other cases, as a match-safe; therefore while entitling this design as a figure for lamp-base I wish to be understood as claiming the design for the figure for whatever purpose used.

I claim as my invention—

The design for figure for lamp-base, as described and shown in the accompanying illustration.

DAVID MOSMAN.
